Dec. 806

Samuel W. Gibbs, of Albany, N. Y. assignor to
Treadwell, Perry & Norton, of Albany, aforesaid.
Letters Patent No. 806. Dated June 17th. 1856.

The Schedule referred to in these Letters Patent, and making part of
the same.

Be it known that I, Samuel W. Gibbs, of the City of Albany, State
of New York, have produced a new ornamental design for a six plate
stove called The Vine pattern, and I hereby declare that the annexed
drawings are full and accurate delineations of the said plates which are
combined to form the Stove with their ornamental parts, a side plate, and
an end plate, not represented being symmetrically similar to their cor-
responding plates shewn, and the legs not shewn being similar to the
one shewn in the drawing.

What I claim as my production and
desire to secure by Letters Patent, is the combination and arrangement

of Ornamental figures and forms represented in the accompanying draw-
ings, forming together the Ornamental design of a six plate Stove.
